UNITED STATES PATENT OFFICE.

JOHN COPELAND, OF QUASQUETON, IOWA.

CHURN.

SPECIFICATION forming part of Letters Patent No. 230,405, dated July 27, 1880.

Application filed April 30, 1880. (No model.)

To all whom it may concern:

Be it known that I, JOHN COPELAND, a citizen of the United States, resident at Quasqueton, in the county of Buchanan and State of Iowa, have invented certain new and useful Improvements in Churns; and I do hereby declare the following to be a full, clear, and exact description of the invention, such as will enable others skilled in the art to which it applies to make and use the same, reference being had to the accompanying drawings, and to letters of reference marked thereon, which form a part of this specification.

This invention relates to improvements in rotary-body churning; and it consists in the construction and arrangement of the several parts, hereinafter described, and pointed out in the claims.

In the drawings, Figure 1 is a vertical longitudinal section, and Fig. 2 is a vertical cross-section, of the body of a churn having my improvements attached thereto, and Figs. 3 and 4 are detail views of the air-pipe.

a is the body, which is provided with trunnions *a'* *a''*, and supported in a suitable frame.

The body may be made of any suitable form.

On the ends *a³* of the box I place a series of breakers, *b*, which are arranged radially, or nearly radially, to axis of motion of the body.

If a round body be employed the breakers would be on the radial lines, but when a polygonal body is employed I prefer to place them at right angles to the sides and slightly off from the radial lines, as will be seen by reference to the positions shown in Fig. 2.

The breakers have one side beveled and the end rounded, as shown, while the opposite side is left straight and vertical to the plane of the end *a³*. The breakers throw the milk away from the ends *a³*.

c c c are a series of longitudinally-hinged flappers or breakers, which are placed on the inner periphery or sides of the box and parallel with the axis of motion. They are arranged alternately with the breakers *b*, and are provided with pins, which are held in guides *d d*. They turn freely on the pins, and will assume a position at right angles to or will lie flat against the sides of the body, as shown.

Fixed between the guides *d d*, and close to the flappers, is a beveled strip, *d'*, which serves

as a stop or shoulder to keep the flapper from turning entirely over. The guides *d* are arranged in pairs, there being a pair for each flapper, and a guide at each end of said flapper, 55 and they have their ends *d²* extended and flared outward from the flapper *d'*, so that their ends are carried to a line or point just in rear of the vertical side of the end breakers, *b*, while their points *d³* are beveled on their outer 60 sides, next the end of the body, so that they will throw the milk outward from the vertical center of the body.

The L-shaped tube *e* is for providing the necessary aeration. Its stem *e'* is passed 65 through the trunnion *a'*, while its stem *e²* is within the churn and is pressed against or very close to the end *a³*. The stem *e²* has its ends closed, while its outer end, *e³*, has made through its side a small opening, *e⁴*, which is 70 partially closed by a tongue, *e⁵*, bent inward, with its outer end near to the closed end *e³*, and just behind the lip *e⁶*. The opening *e⁴* is covered by shield *e⁷*, so arranged as to permit the air or gas to pass freely between it and 75 the stem *e²*. This peculiar construction of the tube permits the free passage of air or gas for all required purposes, and at the same time prevents the milk from getting into the tube. The shield *e⁷* forms a passage-way, open at both 80 ends, so that any milk which may enter at one end will be thrown out by the rotary motion of the churn, and, acting in combination with the tongue *e⁵*, furnishes a perfect guard for the pipe *e²*.

In the operation of the device the box is turned in the direction of the arrows, Fig. 2. The cream is thrown by the guides *d* and flappers *c* laterally against the ends of the body, and behind and against the straight vertical 90 sides of the breakers *b*, which in turn throw it back toward the vertical center, and to be caught by the next pair of guides, by which it will again be thrown laterally, as in the first instance.

The flappers or hinged breakers *c* rise to the vertical position shown in Fig. 2 when the box is turned in the direction of the arrows. When the motion of the body is reversed these hinged breakers lie down flat 100 against the sides, as shown in the upper part of Fig. 1.

After the cream is churned the motion of the body is reversed, and the beveled sides of the breakers *b* and the inward incline of the guides *d* will gather all the butter into a lump 5 at the center, from which it can be easily taken.

After the butter and milk have been removed, and water has been poured into the body, the action of the breakers *b*, guides *d*, and hinged flappers or breakers *c* will wash every particle 10 of milk out of the chamber.

I am aware that in the construction of rotary-body churning it is not new to construct one of its trunnions hollow, so that an aerating tube may be placed therein and revolve with 15 the churn, nor is it new to form the said aerating-tube in the form of an **L**, one wing of which is placed in the hollow trunnion, while the other wing lies inside of and close to the end of the churn, and has its open inner end bent over 20 so as to give it a **U** or bracket shape; nor is it new to construct working-body churning with breakers which are tapering or inclined and arranged on the sides thereof, and I do not claim such constructions; but,

Having thus described my invention, what 25 I claim, and desire to secure by Letters Patent, is—

1. In a rotary-body churn, the series of breakers *b*, fixed on the end boards, *a*³, and arranged radially to the axis of motion, the flappers *c*, 30 hinged to the sides and parallel with the axis of motion of the body and arranged alternately with the breakers *b*, and the flaring guides *d*, arranged in pairs and at opposite ends of the flappers *c*, and stop *d'*, all arranged to operate 35 substantially as and for the purposes set forth.

2. In a rotary-body churn, the **L**-tube *e*, having one of its stems put through the hollow trunnion *a'*, and having its inner stem, *e*², closed at its ends and constructed with a side 40 opening, *e*⁴, provided with an inwardly-inclined tongue, *e*⁵, and the shield *e*⁷, placed over the opening or mouth *e*⁴, and providing a passageway, open at both ends, between it and the pipe *e*², substantially as set forth, and for the purpose specified.

In testimony that I claim the foregoing I have hereunto set my hand and seal this 2d day of April, 1880.

JOHN COPELAND. [L. S.]
